UNITED STATES PATENT OFFICE.

GEORGE F. GALE, OF PHILADELPHIA, PENNSYLVANIA.

DESIGN FOR A BROOM.

Specification forming part of Design No. **6,273**, dated November 26, 1872.

To all whom it may concern:

Be it known that I, **GEORGE F. GALE**, of the city and county of Philadelphia, in the State of Pennsylvania, have invented a certain Design for a Broom, of which the following is a specification:

Nature of the Design.

The design consists in an ornamental arrangement of a curved seam and parallel straight seams and wire bands, in connection with a straight tapering neck, and a cylindrical termination thereof, as hereinafter set forth, and as represented in the accompanying drawing, to which reference is made.

Description.

The figure represents a side view of a broom

illustrating the design. A represents the brush or broom proper, and B the handle. z represents a straight tapering neck closely wrapped with wire, which is supported thereon by Hancock braid, y , or its equivalent. z^2 represents a cylindrical termination of the neck z . x represents a wire band at the base of the neck; and $w w^2 w^3$, parallel bands on the cylindrical terminal z^2 . v represents a curved seam; and $u u^2$, parallel straight seams for confining the straw in the body of the broom.

I claim—

The design for a broom, substantially as above set forth.

GEO. F. GALE.
